UNITED STATES PATENT OFFICE

HERBERT J. MELVILLE, OF CHICAGO, ILLINOIS

RECEPTACLE-CLOSURE MEANS

Application filed January 18, 1928. Serial No. 247,471.

This invention relates to refuse containers, and more particularly to ash receptacles, although certain features thereof may be employed with equal advantage for other purposes.

It contemplates more especially the provision of means for effecting the normal closure of receptacles which readily admit refuse therein for concealment from sight and to avoid obnoxious odors.

Known receptacle closure means are not especially adapted to admit the contents thereto without subjecting the approximate environment to the odors and distasteful appearance resulting therefrom. The fact is that known ash receptacles soon become obnoxious and most disagreeable owing to the smoldering contents thereof which ordinarily are not concealed from the exterior.

As a consequence these are not very desirable for domestic use in that the surrounding atmosphere is materially affected thereby.

With the general indulgence in cigarette smoking by the fairer sex, much annoyance is caused by the refuse incident thereto, since such is most disagreeable, obnoxious and unsightly.

One object of the present invention is to simplify the construction and improve the operation of the closure devices of the character mentioned.

Another object is the provision of instrumentalities for concealing refuse from sight, and precluding the generation of odors exteriorly of the receptacle.

Still another object is the provision of a receptacle having a normally closed orifice receptive of refuse responsive to varying the position thereof.

A further object is the provision of confronting members arranged to normally gravitate in effecting a closure of a receptacle so as to admit refuse therein responsive to inclining the receptacle.

A still further object is the provision of a receptacle having means normally gravitating to close the entrance orifice thereof and receptive of refuse responsive to imparting rocking movement thereto.

Still a further object is the provision of confronting members pendently supported for normal gravitation to close the entrance orifice thereof.

Other objects and advantages will appear from the following description of an illustrative embodiment of the present invention.

In the drawings:

Figure 1 is a plan view of a device embodying features of the present invention.

Figure 2 is a sectional view in elevation taken substantially along line II-II of Figure 1.

Figure 3 is a sectional view in elevation taken substantially along line III-III of Figure 1.

Figure 4 is a view similar to Figure 3, showing the device in an inclined position to effect the reception of refuse within the receptacle.

Figure 5 is a plan view of a modified embodiment of the present invention.

Figure 6 is a sectional view in elevation taken substantially along line VI-VI of Figure 5.

Figure 7 is a sectional view taken substantially along line VII-VII of Figure 5, the receptacle being inclined to admit the reception of refuse therein.

Figure 8 is a fragmentary view in elevation of a still further modified embodiment of closure instrumentalities.

The structure selected for illustration comprises a receptacle 10 of any suitable construction, preferably shaped so that the walls thereof terminate in a peripheral flange 11 to define a mouth 12 of any desired contour. The mouth 12 of the receptacle 10 supports, in this instance, a substantially flat plate 13 which is provided with a ridge 14 spaced from the periphery thereof to engage the interior surface of the flange 11 defining the mouth 12, so as to normally maintain the plate 13 in association therewith. It will be observed that the ridge 14 depending from the plate 13 guides the positioning thereof with respect to the receptacle 10, thereby maintaining its assembled relation without interfering with the ready disassociation of the plate 13 from the receptacle.

tacle 10, to enable the removal of the refuse and cleansing of the parts.

As shown, the plate 13 is provided with an orifice 15 defined by inclined confronting flanges 16 struck therefrom to guide refuse therethrough. In order to normally maintain the orifice 15 closed so as to conceal the refuse from sight and preclude the obnoxious odors issuing therefrom, closure means are provided for that purpose. The closure means consist, in this instance, of a pair of orifice closure blocks 17 and 18 which are pendently supported by links 19 and 20 respectively. It is to be noted that the blocks 17 and 18 are provided with inclined surfaces 17' and 18', respectively, which conform with the inclination of the confronting flanges 16 of the top plate 13. The links 19 and 20 have the extremities thereof provided with studs 21 which engage vertically disposed flanges 22 secured to the under side of the plate 13 intermediate the flanges 16. Fasteners 23 engage the lateral faces of the closure blocks 17 and 18, these being carried by the extremities 23' of the opposing links 19 and 20, to normally maintain the blocks 17 and 18 in abutting relation with the flanges 16 to serve as a closure for the orifice 15.

With this arrangement, the pendently supported members 17 and 18 normally gravitate to assume a confronting relation in contact with each other to close the orifice 15. Cigarettes, ashes and other refuse are disposed on the inclined flanges 16 or the closure members 17-18, and lodged within the receptacle 10 by inclining the position thereof so that the members 17-18 will separate owing to the tendency of retaining their vertical suspension in a manner illustrated in Figure 4 owing to the action of gravity thereon.

Obviously both closure members would tend to swing in the same direction and to effect the separation thereof the vertical depending side flanges 22 are provided with inclined surfaces 23 conforming with the normal inclination of the surfaces 17'-18' of the closure members 17 and 18, these terminating in a nib 25 disposed centrally of the orifice 15 so as to preclude the closure members from moving inwardly beyond the median line 26 of the orifice 15. Thus the inclination of the receptacle 10 in a counterclockwise direction (Figure 4) will tend to position the member 17 in its normally closed position while the other member 18 will recede therefrom to admit refuse therebetween.

To enable the inclination of the receptacle with ease the corners thereof are preferably rounded as at 27 thereby facilitating a rolling action in a direction transverse to the axis of the link mountings 21 of the closure members 17 and 18. Obviously the recep-

tacle 10 may be so shaped and balanced as to position the center of gravity centrally thereof at its bottom to normally retain it in a vertical position, thereby insuring the normal erect position thereof which insures the closure of the orifice 15 owing to the gravitation of the members 17-18 in the path thereof. It will be noted that rollers (shown in dotted lines) may be substituted for the closure members 17 and 18, since such are readily cleansed of the refuse. It is altogether possible to use a single closure member so balanced and suspended as to normally close the orifice 15 (see Figure 8).

A modified embodiment disclosed in figures 5, 6 and 7 consists of the receptacle 10' having peripheral flanges 11' to receive a plate 13' which is provided with a depending peripheral flange 14' in contact therewith for support thereon. The plate 13' is provided with an orifice 15' defined by inclined confronting flanges 16'. A peripheral flange 28 is formed interiorly of the receptacle 10' to support a plate 29 which is telescopically received within the receptacle 10'. The plate 29 is provided with a central depression 30 defining surfaces 30 and 31 inclined to intersect centrally of the orifice 15'. Closure means, in this instance rollers 17' and 18' are disposed in the inclined surfaces 31 and 32 respectively, so as to normally gravitate to a position in the path of the orifice 15', they contacting to preclude communication through the orifice 15'. Side flanges 22' disposed intermediate the inclined flanges 16' are provided with arcuate surfaces 24' conforming with the curvature of the rollers 17'-18' to define a nib 25', thereby precluding the gravitation of the rollers 17'-18' past the median line 26' of the orifice 15'.

A substantially rectangular passage 33 is provided in the plate 29 in alignment with the orifice 15' so as to admit the refuse therethrough into the receptacle 10'. It will be apparent that the inclination of the receptacle 10' in a direction transverse of the axes of the rollers 17'-18' will cause the separation thereof to admit refuse through the orifice 15' between the rollers 17'-18' and through the passage 33 to fall within the receptacle 10'. In this instance the exterior bottom edges of the receptacle 10' are rounded as at 27' to facilitate the rocking movement necessary to effect the separation of the rollers 17'-18' in admitting refuse through the orifice against the normal tendency of the rollers to gravitate to a position in the path of the orifice 15', thereby normally effecting the closure of the receptacle 10'.

To accommodate cigarettes, cigars or other smoking implements, arcuate depressions 34 are provided in the top plate 13, so that the ignited extremities thereof will be disposed above the inclined flanges 16' so that the

ashes dropping therefrom will find its way to the orifice 15' without creating a mess about the surroundings. The component parts are readily removable to enable the 5 cleansing of the receptacle and the ready removal of the refuse contents therein.

Various changes may be made in the embodiment of the invention herein specifically described without departing from or sacrificing any of the advantages thereof as defined in the appended claims.

I claim:

1. In a device of the character described, the combination with a receptacle having an orifice, of a closure therefor comprising paired rollers, and a pendent support for said rollers to normally effect the gravitation thereof to shield said receptacle.

2. In a device of the character described, the combination with a receptacle having an orifice, of a closure therefor comprising paired rollers, and a pendent support for said rollers to normally effect the gravitation thereof to shield said receptacle, said 20 pendent support being arranged to remove said rollers from the orifice responsive to imparting an impact to said receptacle.

3. In a device of the character described, the combination with a receptacle having an orifice, of a closure therefor comprising paired rollers, and means supporting said rollers to normally effect the gravitation thereof to closed position, said receptacle being formed to enable the ready inclination 35 thereof to remove said rollers from the orifice.

4. In a device of the character described, the combination with a receptacle having an orifice, of a closure therefor comprising paired rollers, and means supporting said 40 closure to normally effect the gravitation of said rollers to closed position, and means for shifting said rollers responsive to inclining said receptacle.

45 5. In a device of the character described, the combination with a receptacle having an orifice, of members having arcuate surfaces disposed in confronting relation, and means for supporting said members to normally effect the gravitation of said arcuate 50 surfaces into the path of said orifice.

6. In a device of the character described, the combination with a receptacle having an orifice, of rollers disposed in confronting 55 relation, means for normally maintaining said members in the path of said orifice, and pendent supporting links for said members to effect the movement thereof responsive to imparting an impact to said receptacle, thereby admitting refuse through said orifice.

65 7. In a device of the character described, the combination with a receptacle having an orifice, of confronting rollers, and means

for supporting said rollers to normally effect the gravitation thereof to closed position.

8. In a device of the character described, the combination with a receptacle having an orifice, of confronting rollers, links for 70 pendently supporting said rollers to normally effect the gravitation thereof to closed position, and means on said receptacle enabling the inclination thereof to effect the separation of said rollers to admit 75 refuse through said orifice.
